ROLLER PRESSER BACKSTOP DEVICE FOR
SEWING MACHINESGeorge W. Wesson, Bridgeport, Conn., assignor
to The Singer Manufacturing Company, Elizabeth, N. J., a corporation of New Jersey

Application February 17, 1938, Serial No. 190,907

5 Claims. (Cl. 112—235)

This invention relates to improvements in devices for preventing retrograde rotation of sewing machine presser-rollers and has for its object to simplify and improve the efficiency of 5 back-stop devices of this character.

The invention consists in the presser-roller back-stop device hereinafter described in connection with the accompanying drawing which illustrates a preferred embodiment of the invention and in which:

Fig. 1 is an enlarged side elevation of a roller-presser having the improved back-stop device, as viewed from the side opposite to the sewing machine needle. Fig. 2 represents a front elevation, 15 partly in section, of the roller-presser. Fig. 3 illustrates, in perspective, the back-stop detents and the holder therefor in detached relationship. Fig. 4 illustrates a further enlarged perspective of the detents in engagement with a fragment of 20 the toothed presser-roller hub.

The roller-presser illustrated in the drawing is of well known construction and is employed in a sewing machine having a cloth-plate 1 and a vertically reciprocatory needle-bar 2 carrying a 25 needle 3, said roller-presser including a presser-roller 4 having a knurled peripheral work-engaging surface 5 and a cylindrical hub 6. The hub 6 has an internal rib 7 providing spaced annular recesses, as 8 and 9, for two sets of bearing-balls, 30 as 10 and 11. The bearing-balls 10 roll upon a bearing-cone 12 of a presser-roller supporting screw-stud 13 having a ball-retaining flange 14 at one end thereof. Threaded upon the screw-stud 13 is a shouldered bearing-cone 15 for the 35 balls 11, the screw-stud being itself threaded into the free end of a supporting arm 16 and secured by means of a nut 17. The supporting arm 16 extends forwardly from a roller-presser bracket 18, to which it is adjustably secured by a screw 40 19.

The cylindrical hub 6 of the presser-roller is annularly provided with serrations 20 which lengthwise extend parallel to the axis of rotation of the presser-roller, so that said hub 6 45 is in effect a ratchet-wheel. Resiliently engaging the teeth 20 to prevent retrograde rotation of the presser-roller are adjacent detents 21 and 22 comprising, in the preferred embodiment thereof, laterally spaced prongs of a flexible leaf-spring 23. The end of the leaf-spring 23 opposite to the pronged end thereof is secured by a screw 24 against a flattened face 25 provided upon a lateral extension of a carrier 26, said screw 24 passing through an aperture 27 in the leaf-spring. The carrier 26 extends rigidly from the

supporting arm 16 and in the present case is secured to said supporting arm by a screw 28 having a left-handed thread, said screw passing through an aperture 29 in one end of the carrier 26. The described securing means for the carrier, while simple, has the advantage that the screw is tightened responsively to a retrograde rotation thrust of the presser-roller 4 upon the detent-prongs 21, 22 so that said detent-prongs are securely held against endwise movement. 10

The detent-prong 22 is preferably slightly longer than the prong 21 whereby the spacing of the free ends of said prongs circumferentially of the serrations is less than the width of one tooth, so as to minimize the permissible extent 15 of retrograde rotation of the presser-roller 4.

The presser-roller 4 is journaled in ball-bearings to provide for free rotation thereof when the work is advanced in the direction of the arrow shown in Fig. 1 of the drawing. However, 20 cross-seams and similar obstructions in the work tend to induce retrograde rotation of the presser-roller when freely rotatable, thereby retarding the advance of the work and causing the formation of shortened stitches and the cutting of work, 25 such as leather, by the needle 3.

In order to retain the advantages inherent in a freely rotatable presser-roller, the back-stop detents employed to engage the serrations 20 must necessarily engage said serrations lightly, to obviate retarding the presser-roller. In other words, the leaf-spring prongs 21, 22, must be highly flexible. Nevertheless, it is of course essential for said detents to effectively withstand the thrust imparted thereto by an induced retrograde rotation of the presser-roller. 30 35

In accordance with the present invention, the requisite flexibility and the light pressure of the detents 21, 22 upon the serrations 20 are obtained by employing the thin leaf-spring 23. The leaf-spring 23 is supported by the carrier 26 so as to be disposed substantially tangential to the hub 6 and preferably with both detent-prongs 21, 22 slightly flexed, at all times, in the direction of movement of the prongs to climb the crests of the serrations. Consequently, any retrograde rotation thrust of the presser-roller will always tend to further flex the detents 21, 22 in the direction of the constant flex thereof. However, according to the present invention, said further flexing of the detent-prongs is limited by a backing-member 30 which underlies said detent-prongs. The backing member 30 is preferably in the form of a lug depending from the lateral extension of the leaf-spring carrier 26, the face of said lug 50 55

which is proximate to the detent-prongs 21, 22, being flush with the flat face 25 of said carrier. As will be readily understood, the backing member 30 provides the reinforcement for the thin 5 detent-prongs necessary to prevent said prongs from springing out of engagement with the serrations 20 under a retrograde rotation thrust of the presser-roller. Furthermore, while said backing member 30 permits the detent-prongs to resiliently ride the serrations 20 in the normal 10 direction of rotation of the presser-roller 4, said backing member 30 serves to stiffen the detent-prongs under a retrograde rotation thrust of the presser-roller, thereby effectually limiting retrograde rotation of the presser-roller to a minimum.

15 Having thus set forth the nature of the invention, what I claim herein is:

1. A presser-device for sewing machines, comprising a support, a work-engaging presser-roller 20 rotatably journaled upon said support and annularly provided with serrations, a detent disposed to resiliently engage said serrations and thereby prevent retrograde rotation of said presser-roller, means for supporting said detent against endwise 25 movement, and a backing member disposed to limit resilient movement of said detent in one direction in response to a retrograde rotation thrust of said presser-roller.

2. A presser-device for sewing machines, comprising a support, a work-engaging presser-roller 30 rotatably journaled upon said support and annularly provided with serrations, a flexible detent disposed to resiliently engage said serrations and thereby prevent retrograde rotation of said 35 presser-roller, said detent being flexed in one direction, supporting means for said detent, and means disposed to limit the flexing of said detent in said direction in response to a retrograde rotation thrust of said presser-roller.

3. A presser-device for sewing machines, comprising a support, a work-engaging presser-roller rotatably journaled upon said support and having a peripherally serrated cylindrical hub, a flexible detent substantially tangential to said hub and having one end thereof in resilient engagement with the hub serrations, supporting means for said detent spaced from said hub, and a backing member underlying said detent between the ends thereof in position to limit flexing of said detent in one direction.

4. A presser-device for sewing machines, comprising a support, a work-engaging presser-roller rotatably journaled upon said support and annularly provided with serrations, a pair of flexible detents disposed to resiliently engage said serrations, said detents being both flexed in the same direction, means for supporting said detents, and means disposed to limit the flexing of both of said detents in said direction in response to a retrograde rotation thrust of said presser-roller.

5. A presser-device for sewing machines, comprising a bracket having a supporting arm, a work-engaging presser-roller rotatably journaled upon said arm and having a peripherally serrated cylindrical hub, a carrier extending from said arm, a leaf-spring secured to said carrier-arm and providing detent-prongs of unequal lengths, 25 said detent-prongs being disposed to resiliently engage said serrations and being flexed in one direction, and a backing member extending from said carrier to underlie said detent-prongs in 30 position to limit the flexing thereof in response to a retrograde rotation thrust of said presser-roller.

GEORGE W. WESSON.
